United States Patent Office

Des. 179,757
Patented Feb. 26, 1957

179,757

KEY HOLDER

George W. Bosch, Alameda, Calif.

Application January 16, 1956, Serial No. 39,777

Term of patent 14 years

(Cl. D17—14)

FIG. 1

FIG. 2

FIG. 3

FIG. 4

FIG. 5

Fig. 1 is a perspective view of a key holder showing my new design;

Fig. 2 is a side elevational view of the design as seen from a position at the left of Fig. 1;

Fig. 3 is a top plan view of Fig. 2;

Fig. 4 is a view of aspect similar to Fig. 2, but showing the key retainer in open position; and

Fig. 5 is a left end elevational view of Fig. 3.

The broken lines appearing in Fig. 1 are for illustrative purposes only.

I claim:

The ornamental design for a key holder, substantially as shown and described.
